PLAY YARD

William H. Hurlin, Antrim, N. H.

Application March 8, 1939, Serial No. 260,472

12 Claims. (Cl. 5—99)

My invention relates to play yards or pens for children and the object thereof is to provide a novel and simple folding structure which will overcome the objections to play pens as heretofore constructed.

Heretofore, play yards or pens have been made with a collapsible or foldable fence and bottom or floor sections hinged therein at opposite sides, it being necessary to swing the floor sections upwardly and outwardly within and against the inner faces of two opposite parallel sides, but with much difficulty in holding both sections up at the same time so that the other two opposite parallel sides or ends at right angles thereto could be folded or collapsed inwardly. Owing to the fact that the floor holds the frame or fence rectangular, it follows that when the sections thereof are swung up, the frame would become distorted in shape from a true rectangle and the edges of the floor sections catch on the rungs or projections on the inside of the frame or fence sides to interfere with the collapsing, and this is also true when setting up or extending the device.

The object of the present invention is to provide a play yard in which the fence sits on the floor instead of the floor being mounted and fitting within the fence, so that the fence, which is anchored to the floor, may be readily extended or collapsed without the objections to prior structures as above pointed out, and the floor which embodies an intermediate or central anchoring section and sections hinged on each side thereof, may be swung upwardly against the outsides, that is, against the outer faces of two opposed rigid sides of the fence in collapsing the play yard or pen or downwardly and then the fence extended thereover in an extremely simple manner.

A further object is to provide means to securely hold the play yard extended and means to hold the same in collapsed condition.

Other objects and advantages will appear hereinafter and be brought out more fully in the following specification, reference being had to the accompanying drawings, wherein:

45 Fig. 1 is a plan view of the play yard in an open position, and shown collapsed in dotted lines;

50 Fig. 2 is a vertical section taken on the line 2—2 of Fig. 1 of the lower part;

55 Fig. 3 is an end elevation of the device folded as shown in Fig. 1;

Fig. 4 is a side elevation on a reduced scale;

Fig. 5 is an elevation of another side or end, taken at right angles to Fig. 4;

Fig. 6 is an enlarged fragmentary section taken on the line 6—6 of Fig. 4;

Fig. 7 is a fragmentary plan view of one end of the central or anchoring section of the floor;

Fig. 8 is a similar view of another form; and

Fig. 9 is a fragmentary view of the upper rail of one end.

Referring more particularly to the drawings, the play yard or pen is shown as comprising a central anchoring section 10 preferably consisting of a single elongated and relatively heavy board provided intermediately of its width and at each end with inwardly extending vertical slots 11 having communicating enlargements or recesses 12 of semi-circular or other form on opposite sides of the slots 11 at the free ends thereof in the upper portions of the central section and also formed with reduced portions forming transverse depressed seats or grooves 13 as shown more particularly in Fig. 7. As shown in Fig. 8, a shoulder or retaining wall 15 may be provided outwardly of the groove or seat 14 for a purpose to be hereinafter explained. The floor in addition to including the central anchoring section 10 also includes foldable side sections 16 hinged thereto to swing to horizontal or vertical positions. These sections include parallel cleats or boards 17 hinged at right angles to the central section at their inner ends as shown at 18, three of such cleats being preferably employed at the center and near the ends of the floor. Floor boards 19 are nailed or otherwise secured on these cleats, the free ends of which project beyond the boards and are provided with transverse notches 20 at the top. Risers or feet 10a may be provided for the central anchoring section at the ends thereof to support it off of the floor and assist in sustaining the weight of the child.

The play yard or pen proper has a fence portion forming an enclosure designated generally 21 and having two long sides 22 consisting of upper rails 23 and lower rails 24 which are designed to fit in the notches 20 when the sections 16 of the floor are lowered from a vertical folded position to a horizontal position for use as shown in Fig. 6 and to keep the sides from expanding or displacing outwardly or inwardly. Corner posts 25 may also be provided and the top and bottom rails 23 and 24 are rigidly connected thereto in such a manner as to provide feet 25a formed by the lower projecting ends of the corner posts to act as risers so that the floor of the yard is supported off of the floor surface of a room. Rungs 26 rigidly connect the upper and lower rails and between the two widely spaced central

rungs, a panel 27 is provided at the bottom, if desired. The upper portion may be provided with a counter consisting of horizontal wires of bars 28 and spools or beads 29 slidably mounted thereon.

The collapsible sides or ends are designated at 30, these constituting the other opposed sides of the rectangular enclosure structure and each consisting of two sections 31 with upper and 10 lower rails 32 and 33 connected by rungs 34. These sections are hinged at the center and on the outside of the adjacent or abutting inner ends of the upper and lower rails 32 and 33 as at 35 so as to permit the sectional foldable ends to collapse or 15 fold inwardly over the floor and central anchoring section thereof or to extend out into alignment in the folded or collapsed and extended positions respectively of the device. The outer ends of the upper and lower rails 32 and 33 are hinged at 20 the inside to the corner posts 25 as shown at 36 which in conjunction with the hinges 35 permit the ends to fold or collapse inward as described.

In order to somewhat resiliently but firmly connect the fence or enclosure structure of the 25 yard or pen to be movably or slidably connected to the floor and particularly the central anchoring section thereof, suitable loose play connections are provided between the ends or collapsible sides 30 at the center and the floor at the anchoring section, the same consisting of suitable 30 metallic strap irons or arms 38 secured to the bottom of each end 30 beneath the lower rails 33 of one section thereof and each arm is provided with an aperture 39 to take a bolt 40 so 35 that the latter will extend through a corresponding slot 11 and be held by a nut 41 threaded on the lower projecting end of each bolt. This provides the main connection between the enclosure and the floor and when the enclosure 40 or fence is extended as shown in full lines in Fig. 1, the bolts ride outwardly in the slots 11 vertically through the central anchoring section and the arms are provided with lugs or curved 45 projections 42 to snap into the recesses 12 so as to hold the foldable ends and the collapsible yard closure or fence extended and from accidentally collapsing inwardly. Sufficient play is allowed 50 at the connections to cause the parts to frictionally engage so that they may be readily snapped into and out of position. That is, the lower rails 33 of the ends or collapsible sides 30 will snap into and out of the grooves or seats 13 or 14 and the lower rails 24 of the rigid sides 22 will snap into and out of the notches or grooves 20 near the outer or free ends of the cleats 17. The ends may be additionally held 55 by a fastener 44 on the inner faces of the upper rail sections of the ends, the same being shown in the form of hooks pivoted to one section of each end and engaging a pin 45 on the other section of each end. However, I do not wish to be limited to this construction as any other suitable fastener may be provided.

In the use of the device, assuming that the 60 same is folded as shown in dotted lines in Fig. 1 and in Fig. 3, the floor sections 16 are first dropped down from vertical to horizontal positions and then the whole yard closure or fence is extended to move the sides outwardly over the 65 floor sections from above the central anchoring section, the ends opening outwardly as the bolts 40 move outwardly in the slots 11. When the lugs 42 snap into the recesses 12 with the lower 70 rails of the ends engaging the grooves or seats 13 or 14 and the lower rails of the sides snapping

into the notches or grooves 20, the device will be rigidly held in an extended position. In collapsing the device, these parts are disengaged and the hinged ends folded inwardly moving the bolts to the inner ends of the slots as shown in dotted lines in Fig. 1 and moving the sides 22 inwardly parallel to the long edges of and over the central anchoring section 10 within said edges. The side floor sections 16 are then swung upwardly against the sides of the yard closure or fence so that the 10 device will be compactly folded to occupy a minimum of space when not in use, thereby facilitating storage as well as transportation and handling.

Suitable means such as a strap 46 may be employed to hold the yard collapsed, the same connecting the sides or folded floor sections as shown in Fig. 3.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent, is:

1. A play yard including a sectional floor including an anchoring section and side sections adapted to engage opposite sides of the fence when collapsed, a collapsible fence having slidable connection with the anchoring section and means to hold the parts collapsed.

2. A play yard including a sectional floor including a central section and side sections hinged thereto, a fence having two opposed collapsible sides and movably connected to the central section of the floor to be collapsed or extended over the floor said floor having means to engage and hold the fence sides at the bottom when extended to retain the play yard extended.

3. A play yard including a sectional floor including a central section and side sections hinged thereto, a fence having at least two opposed collapsible sides slidably connected to the floor, said floor having means to engage and hold the fence sides at the bottom when extended to retain the play yard extended, and means to hold the parts in collapsed position.

4. A play yard comprising a collapsible fence having two rigid sides and two foldable sides hinged to the rigid sides and comprising sections hinged to each other, a floor including an anchoring section and oppositely foldable side sections hinged thereto, and means to slidably connect the hinged sections of the fence to the anchoring section to move in and out to collapsed and extended positions.

5. A play yard comprising a collapsible fence having two rigid sides and two foldable sides hinged to the rigid sides and comprising sections hinged to each other, a floor including an anchoring section and oppositely foldable side sections hinged thereto, means to slidably connect the hinged sections of the fence to the anchoring section to move in and out to collapsed and extended positions, and said floor having seats into and out of which the bottom portions of the fence sections snap when extended or collapsed.

6. A play yard including a floor comprising a central section and sections hinged to opposite

sides thereof, a collapsible fence resting on the floor and sliding connections between the collapsible portions of the fence at the bottom and the floor to hold the floor and fence extended and whereby the same may be collapsed.

5 7. A play yard including a floor comprising a central section and sections hinged to opposite sides thereof, a collapsible fence resting on the floor, means to slidably connect the fence to the 10 central section, and means to retain the fence on the floor in extended or collapsed condition.

10 8. A play yard including a sectional floor comprising a central section and side sections hinged to opposite edges thereof to swing upwardly, a 15 fence having two opposed collapsible sides slidably connected to the central section to move inwardly or outwardly with respect to the ends thereof, means to bind the fence in either position, said fence being supported entirely above 20 the floor and on the floor at two opposed sides and means to hold the fence open.

20 9. A play yard including a collapsible fence, a sectional floor comprising a central anchoring section and side sections hinged thereto, slidable 25 connections between the fence and central section, said side sections adapted to fold up against two opposed sides of the fence at the outside when the fence is collapsed, and means to hold the parts extended.

25 30 10. In a play yard having a collapsible fence

with two hinged side sections, a floor comprising a central supporting section and sections collapsibly connected at opposite edges thereof and means to retain the hinged side sections in association with the central supporting section when the fence is extended or collapsed, the sections of the floor connected to the supporting section adapted to move against opposed sides of the fence when the latter is collapsed.

5 11. In a play yard, a floor for fences having 10 two opposed collapsible sides and two opposed rigid sides, said floor comprising a central section and sections hinged to opposite sides thereof, said central section having movable means of connection with the opposed collapsible sides of the 15 fence whereby the latter is retained in operative connection with the central section when collapsed or extended.

12. A play yard including a sectional floor comprising three hinged sections, a collapsible 20 fence having opposed pairs of sides hingedly connected at the corners, two of said sides being rigid, two of said sides being foldable inwardly over a section of the floor and having movable connection therewith, the other sections of the 25 floor adapted to swing upwardly against the rigid sides when the fence is collapsed, and means to hold the parts collapsed.
